UNITED STATES PATENT OFFICE.

CARL ERIC ANDERSON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,273,714.

Specification of Letters Patent. Patented July 23, 1918.

Application filed March 28, 1918. Serial No. 225,304.

To all whom it may concern:

Be it known that I, CARL ERIC ANDERSON, a citizen of the United States of America, residing at Bridgeport, in the county of 5 Fairfield and State of Connecticut, have invented certain new and useful Improvements in Electric Switches, of which the following is a specification.

My invention relates to electric switches 10 and particularly to push button switches, the object of my invention being to provide means for holding the push buttons in proper position for their most efficient operation and to impart a better appearance 15 to the switch as a whole.

In the accompanying drawings,

Figure 1 is a section on the line 1—1, Fig. 2;

Fig. 2 is a plan of the switch shown in 20 Fig. 1 but with the push button shanks in section;

Fig. 3 is a perspective of the push button positioning spring and portions of the push button shanks.

25 In switches of the present type, the switch mechanism is usually operated by a pair of push buttons freely jointed to a rocker bar pivoted on a frame. Inasmuch as a certain amount of play must be permitted between 30 the push buttons and the guides through which they work, the buttons are loosely confined thereby, with the result that when the switch is mounted on a vertical surface, such as a side wall, the buttons sag against 35 the sides of the guide apertures, and not only give an unworkmanlike appearance to the switch, but also lessen the efficiency of operation by bearing with more or less friction against the sides of the guide apertures. By my present invention, I have 40 provided means for holding the switch buttons in proper position at all times.

In the accompanying drawings, I have 45 illustrated a switch of the type described in my co-pending application, Serial No. 174,743, filed June 14, 1917; but it will be understood that the invention may be applied with equal facility to switches of other construction, and I do not limit my invention to this precise mechanism. As here 50 shown, however, the switch comprises a cup-shaped base 10 of insulating material, carrying at its opposite ends wire terminal straps 11 and 12 for the binding screws 13 and 14. Switch terminals 15 and 16 are se-

cured to the respective straps 11 and 12, and are engaged by the switch blade 17 in the "on" position of the switch, as indicated in Fig. 1. Mounted on the base of the chamber is a frame 18 provided with 60 bosses 19 on which the switch blade 17 pivots. The top of the gable of the frame is notched at 20 to form a bearing for the rocker bar 21 operatively connected to the switch blade 17 through the switch spring 65 22. The opposite ends of the rocker bar 21 are notched at 23 and 24 to form bearings engaged by the studs 25 and 26 at the inner ends of the shanks 27 and 28 of the push buttons 29 and 30. The features described 70 are disclosed in my co-pending application above mentioned, the construction of which is utilized merely to indicate, in a general way, the type of switch to which my present invention relates.

75 The push buttons 29 and 30 are guided by passing through holes in the yoke 31, which are sufficiently large to permit the free play of the push buttons therein. This play is practically necessary in order to accommodate the push buttons freely and to permit a yoke of standard dimensions to be used irrespective of the variation which unavoidably occurs in the firing of the porcelain base. This enlargement of the guide holes 80 permits the sagging of the buttons from a position at right angles to the plane of the yoke, in a manner well known in practice and fairly illustrated in such patents as Platt 1,193,606. To obviate this defect, I 85 now provide a spring plate 32 having studs 33 which overlie the studs 21^a of the rocker bar in the bearing notches 20 in the gable of the frame, while its opposite ends have cross grooves 34 and 35, in which are engaged the lower ends of the shanks 27 and 28 of the push buttons. The constant pressure of this spring bar against the lower 90 ends of the shanks of the push buttons forces the bearing studs 25 and 26 thereof against the upper surfaces of the notch bearings 23 and 24 in the ends of the rocker bar 21, and consequently holds the buttons in right- 95 angular position with relation to the yoke 31 and the face plate 36.

100 By thus maintaining the push buttons constantly at right angles to the face plate, their free passage through the holes therein and in the yoke 31 is assured. At the same time, a workmanlike appearance is imparted 105 110

to the switch which is lacking when the buttons are free to take various angular positions with relation to the face plate and make loose joint with the rocker bar.

3 I claim:—

1. In a push button switch, an oscillating switch bar, an oscillating rocker bar, a switch spring operatively interposed between the same, a pair of switch buttons loosely pivoted to said rocker bar on opposite sides of its axis, and auxiliary spring means for holding said push buttons in proper operating position.
- 10 2. In a push button switch, an oscillating switch bar, an oscillating rocker bar, a switch spring operatively interposed between the same, a face plate covering the switch mechanism, a pair of switch buttons passing through said face plate and loosely pivoted 20 to said rocker bar on opposite sides of its axis, and auxiliary spring means for holding said push buttons substantially at right angles to the plane of the face plate.

3. In a push button switch, an oscillating rocker bar, a pair of push buttons loosely pivoted to said rocker bar, and a spring strap bearing at its opposite ends against the inner ends of the push buttons to maintain the latter in proper operating position. 25

4. In a push button switch, an oscillating rocker bar, a pair of push buttons loosely pivoted to said rocker bar, and a pivoted spring strap bearing at its opposite ends against the inner ends of the push buttons to maintain the latter in proper operating 30 35 position.

5. In a push button switch, an oscillating rocker bar, a pair of push buttons loosely pivoted to said rocker bar, and a spring strap pivoted on the axis of the rocker bar 40 and bearing at its opposite ends against the inner ends of the push buttons to maintain the latter in proper operating position.

In testimony whereof I have signed my name to this specification.

CARL ERIC ANDERSON.
